PORTABLE LAMP

Robert G. Williams, Toledo, Ohio, assignor to The
Usona Manufacturing Co. Inc., Toledo, Ohio,
a corporation of Ohio

Application July 13, 1936, Serial No. 90,349

3 Claims. (Cl. 240—10.68)

This invention relates to electric lamps and more particularly to an electric lamp using a portable source of energy such as dry batteries for the energization of the light source.

5 The invention embraces an improved lamp construction wherein the relative position of its component elements controls the circuit connecting the source of energy with the light source.

An object of the invention is the provision of a 10 portable lamp construction in which the electric circuit for the energization of the light source is established by the relative movement of the light source with respect to other component elements of the lamp thus eliminating the use of additional switching means.

Another object of the present invention is a simplified novel construction for portable lamps wherein the flow of current is controlled by the 15 position of the light discharging head with respect to the portion of the housing which encloses the source of energy, and wherein the light discharging head constitutes a removable unit.

Further objects of the invention reside in the 20 provision of a simplified lamp construction having a novel arrangement of its constituent parts so that positive electrical connections are made when energization of the light source takes place.

Further objects and advantages are within the 25 scope of this invention such as relate to the arrangement, operation and function of the related elements of the structure, to various details of construction and to combinations of parts, elements per se, and to economies of manufacture and numerous other features as will be apparent 30 from a consideration of the specification and drawing of a form of the invention, which may be preferred, in which:

Figure 1 is an elevational view of the lamp embodying the invention with a portion of the housing removed for the purpose of showing the elements which control the energization of the light source;

Figure 2 is a top plan view of the lamp shown in Figure 1;

Figure 3 is a fragmentary view showing the position of the elements of the lamp when the light source is energized;

Figure 4 is a sectional view taken substantially in the plane indicated by line 4—4 of Figure 1 looking in the direction of the arrows;

Figure 5 is an enlarged isometric view illustrating the type of light source supporting means and light bulb shown in Figure 1;

Figure 6 is a view similar to Figure 1 illustrating a modified form of the invention;

Figure 7 is an isometric view partially in section illustrating the type of light source supporting means shown in Figure 6;

Figure 8 is a view similar to Figure 1 illustrating another modified form of the invention.

The invention is illustrated as embodied in a portable electric lamp of the type commonly known as flashlights but it is understood that I contemplate its use wherever the features of the invention may be found of utility. It is understood that I do not wish to limit the invention to the forms shown but that the same are used for illustration purposes only.

The invention in one of its general aspects embraces a lamp construction including two unitary 15 sub-assemblies, one constituting a light emitting head carrying and supporting the light source, and the other an enclosure acting as current conducting and support means for a current source, the two sub-assemblies being so arranged that 20 relative movement therebetween establishes a circuit for the flow of energy from the current source to the light source to energize the latter.

Referring particularly to Figures 1 to 5 showing an embodiment of the invention, the portable lamp construction illustrated comprises two unitary sub-assemblies, one constituting the light emitting head 10 and the other the housing or enclosure 12 for a suitable source of current. The housing 12 is made preferably of tubular configuration closed at one end and preferably made of current conductive material of thin cross section or provided with metallic lining serving as current conducting means. Frictionally retained by an annular recess 15 formed adjacent to the closed end of the housing 12 is a resilient member or spring 14 having a portion in positive contact with the side walls and bottom of the housing 12. The spring 14 is adapted to resiliently support a suitable source of current such as dry cells 16 and 17 by engaging the bottom wall of the dry cell housing or one terminal thereof. The outer wall of the open end of the housing 12 is formed with suitable threads 19 serving as means for connecting and retaining in proper relation the 35 light emitting head 10 and housing 12.

The light emitting head 10 is preferably formed of a non-conductive translucent material of cap like configuration comprising an end wall portion 20 and a dependent tubular portion 21 of 50 a suitable inside diameter for the purpose of surrounding the housing 12 at its open end portion. I have found that a plastic composition serves the purpose very effectively. The inner surface of the tubular portion 21 of the light emitting 55

- head 10 is provided with threads 22 formed thereon serving as means for connecting and holding in position the light emitting head 10 on the housing 12 thus closing the open end thereof.
- 5 The light emitting head 10 removably carries adjacent to the end wall portion 20 a lamp support 24 which in the form shown is supported by engaging the threaded portion 22 and can be adjusted and retained in desired position by said 10 type of connection.
- The lamp supporting member 24 is made of thin resilient current conductive material preferably of a V type formation with flat edge portions 25 and 26 provided with a central opening adapted 15 to receive a threaded tubular member 29 for the purpose of removably supporting the lamp bulb 30 carrying the source of light or filament 32 by engagement with the metallic threaded member or base terminal 33. It should be noted that one 20 terminal of the filament 32 is connected to the threaded member 33 while the other terminal is connected to contacting member 35 which is in contact with the central terminal 37 of the uppermost cell 17.
- 25 The light emitting head 10 is provided at its end wall portion 20 with a conical bore 38 terminating into an opening 40 of lesser diameter than the diameter of the lamp bulb. When the sub-assemblies are in the position shown in Figure 30 1, the circuit between the source of current or batteries 16 and 17 and the lamp bulb filament 32 is open and under this condition the central electrode or terminal or the dry cell 17 is urged into positive contact with the lamp base terminal 35 by the action of the spring 14.
- In order to energize the lamp source 32 it will 35 only be sufficient to move either the light emitting head 10 or the housing 12 toward the other. In the form shown, the turning action of either 40 member toward the other will cause the engagement of the end wall of the open end of housing 12 with one of flat portions 25 or 26 of the lamp support 24. The position of these members when the light source is energized is particularly shown 45 in Fig. 3. Whenever the user desires to open the circuit for interrupting the flow of current from the dry cells 16 and 17 to the lamp bulb filament 32, it will only be necessary to impart rotation to the light emitting head 10 or housing 12 in the 50 opposite direction so as to disengage the end of the housing 12 with either of flange portions 25 or 26 of the lamp supporting member 24.
- In the form of the invention particularly shown 55 in Figures 1 to 5, the lamp supporting member 24 is made of resilient or spring material for the purpose of permitting slight decrease in its maximum diameter which can be accomplished by the compression or movement of the inclined wall sections 41 and 42 in order to increase the facility of assembly and removal of this member 60 upon the light emitting head 10 without the necessity of turning the same with respect thereto. The flat portions 25 and 26 of the lamp supporting member 24 are made of a suitable angularity or having the proper surface inclination so as to 65 allow a screw thread connection with the inner thread portion 22 of the light emitting head 10 permitting the desired adjustment for proper positioning of the lamp bulb 30 and filament 32 70 with respect to the end wall 20 of the light emitting head 10.

As hereinbefore described, the flow of current to cause the emission of light through the light emitting head 10 is controlled by the relative movement of the light emitting head 10 with 75

respect to the housing 12 which movement is permitted due to the compression of spring member 14 which resiliently supports the batteries 16 and 17.

The flow of current for the energization of the filament 32 utilizes a circuit which comprises from the bottom wall of the housing of battery 16 which forms one of its terminals being in direct contact with spring 14 to the bottom of the housing 12 and through the conductive lining or walls thereof to the end of the threaded portion 19 which is in engagement with flat portions 25 or 26 of the lamp support 24 and through the threaded member 29 to the lamp filament terminal 33, through filament 32 to its other terminal 15 35 connected to the central terminal 37 of the dry cell 17 serially connected with cell 16.

In the form of the invention shown in Figures 1 to 5 inclusive, I have found it very effective to use a translucent plastic composition for the light emitting head provided with a central opening with a lamp bulb held in tight engagement with said opening so that an air tight closure is provided for the lamp bulb and source of current. In addition, this type of arrangement 25 emits a direct light beam having a diffused light adjacent to the light source.

Referring to another form of the invention shown in Figures 6 and 7, the lamp construction comprises an open ended metallic casing 50 30 adapted to receive and enclose a light source in the form of a dry cell 52, having one terminal connected to the housing 50 by means of a resilient member 53 and being provided at its open end with threaded portion 55 on which is supported 35 a light emitting head 56 by means of the threads 58 formed at the inner wall of the tubular section 60 of the light emitting head 56.

The light emitting head is provided at its end wall with a central conical bore 62 terminating 40 into an opening 64 of smaller diameter than the lamp bulb 65. Lamp bulb 65 is supported within the light emitting head 56 by disc like member 66 of current conductive material provided with a threaded tubular member 67 adapted to accommodate and receive the lamp bulb base 68. The lamp bulb supporting member 66 is provided at its peripheral edge portion 70 with threads 71 for the purpose of mounting the same in any desired position within the light emitting head 56 by utilizing the threads 58. In this form of the invention the member 66 is provided with a highly polished face 72 for the purpose of reflecting any light directed thereto through the light emitting head, thus increasing the light projected by the 55 energization of the filament of lamp bulb 65.

In the form of the invention shown in Figures 6 and 7 the current flow which energizes the lamp bulb is controlled by relative movement of the light emitting head 56 with reference to the 60 metallic casing 50 which movement is imparted by the user by screwing or turning the housing 50 or light emitting head 56 toward each other, which movement causes the engagement of the end wall of the housing with the inner wall of 65 the light supporting member 66. In this form of the invention the circuit is also interrupted by unscrewing or turning in the opposite direction the light emitting head 56 or housing 50. The elements which have herein been described as 70 forming circuit connection for the energization of the lamp bulb are also used in this form of the invention.

In the modified form of the invention shown in Figure 8, the portable lamp includes a housing 75

80 and a light emitting head 82, the housing in this case being of current conductive material and being connected to one terminal of the battery by the use of a resilient member 83. The 5 housing 80 is also provided with threaded portion 84 on which is threaded the light emitting head 82. In this form of the invention the light emitting head comprises a tubular member 85 of insulating material having a threaded portion 86 10 at its inner wall and adapted to support a suitable lens 87 and a reflector 88, the lens being held in position between an end flange formed on the tubular member and the reflector peripheral edge which has a threaded engagement with the 15 threaded portion 86 of the tubular member 85. The reflector 88 is made of current conductive material and supports a light bulb 90 by engaging a terminal thereof providing a current conducting means adapted to be engaged by the end of 20 the housing for causing the energization of the lamp bulb filament. In this form of the invention the energization of the lamp bulb is controlled by relative motion between the light emitting head 82 and the housing 80 causing engagement 25 of the peripheral edge of reflector 88 with the end wall of housing 80.

I have shown a threaded connection between the light emitting head and the housing in the 30 embodiments of the invention as means to provide a quick assembly of the two unitary sub-assemblies of the portable lamp and as means for providing an easy method of control for the energization of the light source. However, it is to be understood that other connections may be 35 used without departing from the spirit of the invention.

It is apparent that within the scope of the invention, modifications and different arrangements may be made other than is herein disclosed, and the present disclosure is illustrative merely, the invention comprehending all variations thereof.

What I claim is:

1. A portable electric lamp including a housing 45 having current conducting means and provided with an open end formed with threads; a light emitting head of translucent material having an end wall formed with a central opening and a tubular portion embracing said housing 50 and provided with threads at its inner wall whereby the head engages and closes the end of said housing; a resilient current conducting member engaging the threads of said head and adjustably carried thereby having converging walls and a 55 central opening for supporting a lamp bulb by engaging a terminal thereof, said current conducting member being located in close proximity to the end wall of said housing whereby relative movement between the housing and head will 60 cause the engagement of the current conducting

member and housing current conducting means for establishing an energizing circuit for the lamp bulb; and resilient means contacting with said housing conducting means and adapted to resiliently support within the housing a source of current by engaging a terminal thereof and urging said source of current toward the open end of the housing whereby its other terminal is in engagement with the other terminal of the lamp bulb and movement between said head and housing 10 serves to flex said resilient means.

2. In a flash light, in combination, a housing having an open end formed with threads and being provided with current conducting means; a non-conductive translucent member having an 15 end wall formed with an opening and having a tubular portion with threads at its inner wall whereby the member is connected for relative movement on said housing and is adapted to close the open end thereof; the walls of said member 20 adjacent to said opening forming a stop and having portions adapted to engage a lamp bulb; a current conducting element adjustably supported by the threaded tubular portion of said non-conductive member for supporting a lamp 25 bulb in engagement with the walls of said member adjacent said opening, the current conducting element serving as a portion of the circuit used for energizing the lamp bulb, the relationship of the non-conductive member and the current conducting means of the housing being such that movement of one towards the other causes the engagement of the current conducting member with the current conducting means of the housing. 30

3. In a flash light, in combination, a housing having an open end formed with threads and being provided with current conducting means; a non-conductive translucent member having an end wall formed with an axial bore terminating 40 into an opening and having a tubular portion with threads at its inner wall whereby the member is connected for relative movement on said housing and is adapted to close the open end thereof; the walls of said member adjacent to 45 said axial bore serving as a stop and having portions which engage a lamp bulb; a resilient current conducting element adjustably supported on the threaded tubular portion of said non-conductive member and adapted to support a lamp 50 bulb in engagement with the walls of the axial bore, the resilient conducting element serving as a portion of the circuit used for energizing the lamp bulb, the relative position of the non-conductive member and the current conducting 55 means of the housing being such that relative movement therebetween causes the engagement of the resilient current conducting element with the current conducting means of the housing.

ROBERT G. WILLIAMS. 60
